UNITED STATES PATENT OFFICE.

THOMAS P. GREGER, OF PHILADELPHIA, PENNSYLVANIA.

DESIGN FOR A MANHOLE-COVER.

SPECIFICATION forming part of Design No. 28,070, dated December 21, 1897.

Application filed October 8, 1897. Serial No. 654,597. Term of patent 14 years.

To all whom it may concern:

Be it known that I, THOMAS P. GREGER, a citizen of the United States, residing at the city of Philadelphia, in the county of Philadelphia and State of Pennsylvania, have invented and produced a new and original Design for a Manhole-Cover, of which the following is a specification, reference being had to the accompanying drawings, forming part thereof, in which—

Figure 1 is a top or plan view of a manhole-cover, showing the particular shape or configuration of the cover of my said design; and Fig. 2 is a vertical sectional view on the line $\alpha\alpha$ of Fig. 1 of the drawings, these two views being deemed essential to a proper disclosure in detail of the leading feature of my invention, consisting of the shape or configuration of the manhole-cover of my said design.

As illustrated in the drawings, the cover A is substantially dish shape in cross-section. The top surface of the cover is provided with a series of inwardly-projecting curved and perforated ornaments a , as illustrated in Fig.

1, and the walls of these perforated ornaments are made cone shape or tapering, as illustrated in Fig. 2. The cover has also two block-like ornaments C, disposed opposite, or substantially so, to each other, and adjacent thereto and located toward the periphery 30 of the same are provided two block-like openings D, and around the top edge or rim of the cover are provided concentric ridges or grooves b , as clearly illustrated in Fig. 1 of the drawings.

Having thus described my invention, what I claim as new, and desire to secure by Letters Patent, is—

The design for a manhole-cover, substantially as herein shown and described.

In testimony whereof I have hereunto set my signature in the presence of two subscribing witnesses.

THOMAS P. GREGER.

Witnesses:

J. WALTER DOUGLASS,
THOMAS M. SMITH.
